UNITED STATES PATENT OFFICE.

ALBERT SCHMIDT, OF FLINT, MICHIGAN, ASSIGNEE TO CHAMPION IGNITION COMPANY,
OF FLINT, MICHIGAN, A CORPORATION OF MICHIGAN.

SPARK-PLUG.

1,852,148.

Specification of Letters Patent.

Patented Sept. 7, 1920.

Application filed September 25, 1918. Serial No. 255,574.

To all whom it may concern:

Be it known that I, ALBERT SCHMIDT, a citizen of the United States, and resident of Flint, Genesee county, State of Michigan, have invented certain new and useful Improvements in Spark-Plugs, of which the following is a specification.

The invention relates to improvements in spark plugs, and more particularly to the means for effecting a seal between an insulator and a central electrode supported therein.

The objects of the invention are to devise a simple and durable means for effectually sealing the joint between the central electrode and the insulator, and to effect such seal without subjecting the parts to unnecessary strain or continued stresses.

These and various other objects will clearly appear from the following description, taken in connection with the accompanying drawing which forms a part of this specification.

In the drawing Figure 1 is a side elevation of a spark plug showing the upper portion thereof broken away in sections to illustrate the invention, and Fig. 2 is an elevation view of the upper portion of a spark plug and the central electrode with the terminal nuts and sealing washers removed therefrom and partially in section.

Like numerals of reference indicate similar parts throughout the views.

Referring to the drawing, a spark plug shell 10 is shown having the insulator 11 arranged therein and the central electrode 12 anchored in said insulator and projecting upwardly therefrom, as customary in spark plug construction of the type shown. It must be understood that the particular construction of the shell or insulator is quite immaterial as concerns the present invention, always providing the insulator has the electrode projecting upwardly therefrom and there is occasion to form a seal thereabout.

To form the seal on the top of the insulator and about the central electrode 12, a compression gasket 13, made of material such as asbestos, is provided, the same fitting around the electrode and against the upper end of the insulator.

Next above the compression gasket 13 a sealing washer 14 is arranged, said washer having the under side thereof formed con-

ave and the upper side thereof projecting upwardly in frusto-conical shape as at 15, the central orifice of said washer and through which the central electrode extends, forming with said frusto-conical portion 60 a very thin upper edge 16 about said washer.

The electrode 12 is capped by a terminal nut 17, which is permanently secured in place upon the upper end thereof and which may be of any desired form, the one shown 65 in the drawing being of spherical shape and having the central threaded orifice 18, with the blind end 19 on the interior of said nut and said orifice 18 being flared slightly adjacent the open end to provide a conical 70 surface which fits over the upwardly extending frusto-conical portion of the nut 14.

In assembling the parts to make the seal about the upper end of the electrode, the washer with the compressible gasket is 75 pressed firmly onto the insulator by any suitable die or holding jig and the terminal nut is screwed into position whereby the parts are held with the outer edge periphery of the washer firmly seated upon the compression gasket 13, whereby practically a 80 peripheral line contact is made about the gasket and the outer edge thereof firmly and evenly pressed down onto the top of the insulator 11, much more effectively than 85 would be the case if the washer 14 had a flat under side and pressed over the entire surface of the compression gasket 13. In like manner the nut 17 as it is screwed down over the frusto-conical upper portion of 90 the washer 14 will readily spin inwardly the thin metal and seal the same effectually about the central electrode. At the same time the flared part of the orifice in the nut will seat itself firmly upon the outer face 95 of the frusto-conical upper end of the nut and very effectively seal the joint thereabout coincident with the sealing of the joint between the nut and the insulator by means of the compression gasket 13 as above described.

Particular mention is made of the manner in which the entire seal is made with respect to the materials used, that is, the insulator is preferably made of porcelain and 105 the seal between it and the nut 14 is made entirely by compression means without any rotation thereof, and consequently without stresses or strains upon the porcelain insulator beyond that which it can readily 110

2
sustain, but where the nut is screwed onto the washer, both parts being of metal and the one being comparatively thin, the metal will be firmly pressed into sealing contact about the electrode at a point where the rubbing of one part about the other will not cause objectionable stresses or strains.

It must also be noted that the compression gasket material, as also the upper portion of the sealing nut, is at all times compressed toward the center and in no manner allowed to spread outwardly, whereby the effect of the original seal is always maintained.

15 It must also be noted that the electrode is very slightly spaced away from the orifice in the insulator, whereby the tightening of the sealing members will in no manner cause any lateral stresses where the electrode projects out of the insulator, and in this manner not only is the seal more effectual but the insulator itself properly supported against accidental concussion.

20 While I have described and will specifically claim what I deem to be a preferred embodiment of my invention, it will be obvious to those skilled in the art that various modifications and changes may be made without departure from the spirit and scope 25 thereof.

Having thus described my invention, what I claim and desire to secure by Letters Patent is:

1. In a spark plug, an insulating element 35 and an electrode secured therein and sealed at the protruding end thereof by a sealing member having a compression bearing against said insulator about the lower and outer periphery and against said electrode 40 about the upper and inner periphery thereof.

2. In a spark plug, the combination with an electrode and means for supporting the same in said plug, of a washer about said electrode, and means for forming a compression seal between the outer periphery of 45 said washer and said supporting means and the inner periphery of said washer and said electrode.

3. In a spark plug, an insulator having 50 an electrode anchored therein and projecting thereabove, a sealing washer of substantially frustoconical shape having a concave lower face next said insulator and a tapered upper end next said electrode.

4. In a spark plug, an insulator having 55 an electrode anchored therein and projecting thereabove, a sealing washer of substantially frustoconical shape having a concave lower face next said insulator and a tapered upper end next said electrode, and means 60 for seating said washer onto said insulator and electrode.

5. In a spark plug, an insulator having an electrode anchored therein and projecting thereabove, a gasket of compressible material about said electrode, a sealing washer about said electrode above said gasket and having a concave under surface, and means for seating said washer to compress said gasket about the periphery thereof against 70 said insulator, said seating and compressing means being permanently secured in place upon the free upper end of said electrode.

6. In a spark plug, an insulator having 75 an electrode anchored therein and projecting thereabove, a gasket of compressible material about said electrode, a sealing washer about said electrode above said gasket and having a concave under surface, and an upper part of substantially frustoconical form, 80 and means for seating the washer to compress said gasket about the periphery thereof against said insulator and to seal between the upper end of said washer and said electrode.

7. In a spark plug, an insulator having an electrode anchored therein and projecting thereabove, a gasket of compressible material about said electrode, a sealing washer about said electrode above said gasket and 90 having a concave under surface, and an upper part of substantially frustoconical form, and a nut threaded onto said electrode and compressing said washer and gasket.

8. In a spark plug, an insulator having 95 an electrode anchored therein and projecting thereabove, a gasket of compressible material about said electrode, a sealing washer about said electrode above said gasket and having a concave under surface, and an upper part of substantially frustoconical form, 100 and a terminal nut threaded onto said electrode and fitting over the frustoconical end of said washer to seal the same about said electrode and to compress said gasket and 105 seal the same about said insulator.

In testimony whereof I affix my signature.

ALBERT SCHMIDT.
